UNITED STATES PATENT OFFICE

WILLIAM N. BOOTH, OF DETROIT, MICHIGAN, ASSIGNOR TO KELSEY-HAYES WHEEL CORPORATION, OF DETROIT, MICHIGAN, A CORPORATION OF NEW YORK

DESIGN FOR A DISK WHEEL

Application filed May 13, 1929. Serial No. 31,199. Term of patent 14 years.

To all whom it may concern:

Be it known that I, WILLIAM N. Booth, a citizen of the United States of America, residing at Detroit, in the county of Wayne and State of Michigan, have invented a new, original, and ornamental Design for Disk Wheel, of which the following is a specification, reference being had therein to the accompanying drawings, forming a part thereof, in which—

Figure 1 is a front elevation of a disk

wheel, showing my new design; Figure 2 is a perspective view thereof; Fig. 3 is a diagrammatic mid-section through one-half of the wheel.

I claim:

The ornamental design for a disk wheel substantially as shown.

WILLIAM N. BOOTH.
